UNITED STATES PATENT OFFICE

158,954

SLIPPER

Virginia J. Gilmore, San Francisco, Calif.

Application November 18, 1949, Serial No. 6,120

Term of patent 14 years

(CL. D7—7)

To all whom it may concern:

Be it known that I, Virginia J. Gilmore, a citizen of the United States and a resident of the city and county of San Francisco, State of California, whose post office address is 320 Font Boulevard, San Francisco, California, have invented a new, original, and ornamental Design for a Slipper, of which the following is a specification, reference being had to the accompanying drawing, forming a part hereof.

Fig. 1 is a plan view of a slipper embodying my design;

Fig. 2 is a side elevation of the slipper;

Fig. 3 is a rear end elevation of the slipper, and

Fig. 4 is a front end elevation of the same.

I claim:

The ornamental design for a slipper, as shown.

VIRGINIA J. GILMORE.
